UNITED STATES PATENT OFFICE.

GEORGE H. FARMILO, OF SCHENECTADY, NEW YORK.

FENCE-LOCK.

940,680.

Specification of Letters Patent. Patented Nov. 23, 1909.

Application filed March 2, 1909. Serial No. 480,892.

To all whom it may concern:

Be it known that I, GEORGE H. FARMILO, a citizen of the United States, residing at Schenectady, in the county of Schenectady and State of New York, have invented certain new and useful Improvements in Fence Locks, of which the following is a specification, reference being had therein to the accompanying drawing.

10 This invention relates to a clamp for wire fences, and more particularly to a clamp for securely fastening cross wires or strands together at their crossing points.

15 The object of this invention is the production of a wire clamp for fences, which is simple in construction, efficient in operation and consist of a comparatively small number of parts.

20 Another object of this invention is the provision of means for facilitating the securing of cross wires together at their crossing points.

25 With these and other objects in view this invention consists of certain novel constructions, combinations and arrangement of parts hereinafter described and claimed.

30 In the drawings: Figure 1 is a perspective view of a portion of a fence, showing my improved wire clamp for fences applied thereto; Fig. 2 is an end view of one of the clamp devices; Fig. 3 is a longitudinal section of the clamp; Fig. 4 is an elevation of another embodiment of my invention; and, Fig. 5 is a longitudinal sectional view of 35 said modification.

35 Referring to the drawings by numerals 1 designates a vertical strand or wire and 2 a longitudinally extending strand and these strands are securely fastened at their junction points by means of a clamp-device 3. The clamp-device 3 comprises, preferably, a hollow body portion 4, which is provided with a transversely extending aperture 5, through which is adapted to be positioned, 40 or passed, the vertical strand 1. The body portion 4 is also provided with a longitudinally extending slot 6 in which is adapted to fit the longitudinally extending wire 2, and said slot extends far enough into the body 45 portion so as to allow the transverse, or longitudinally extending strand 2 to bind against, or engage, the vertical strand 1. The slotted end of the body portion 4 is screw-threaded as at 7, and upon this screw-threaded end is 50 adapted to be threaded a nut 8, which nut when threaded upon said end will bind the

longitudinally extending strand 2 against the vertical strand 1 and hold said strands in a firm position. It will also be obvious that by securing or by threading the nut 60 upon the screw-threaded end of the body portion 4 of the clamp, and by having the slot formed in said end the sides will constitute jaws and will be brought toward each other when said nut is threaded upon 65 said end and thereby clamp the longitudinally extending wire more firmly in the slot.

It will be obvious that by having a clamp-device constructed in accordance with the present invention the cross wires can be 70 firmly held in engagement with each other, and held thereon in a set position by means of the clamping action of the nut upon the longitudinally extending strand. Although the vertical strand 1 is shown passing 75 through the transversely extending aperture 5 and the longitudinal strand 2 extending through the longitudinal slots 6, the position of said strands can be reversed and the longitudinally extending strand can be 80 passed through the transversely extending aperture and the vertical strand can be passed through the longitudinally extending slot, as the position of the wires is immaterial for the clamping action of the same 85 will take place without regard to special arrangement of said wires.

In Figs. 4 and 5 I have shown a modification of my invention, which shows a clamp provided with a solid body portion 4^a, 90 through which passes a transversely extending aperture 5^a. Extending from one end and intersecting with said transversely extending aperture is a longitudinally extending slot 6^a, similar to the slot illustrated in 95 Fig. 3 of the preferred embodiment. The end of the clamp, which is provided with a longitudinally extending slot tapers and threads are formed upon said tapering portions, as at 7^a, and it will be obvious that a 100 binding or clamping action will be exerted by having said ends tapering and the sides will be more easily drawn together by having said end tapering.

What I claim is:

105 1. As an article of manufacture, a wire clamp for fences, comprising a body portion provided with a transversely extending aperture, one end of said body portion screw-threaded, and provided with a longitudinally extending slot intersecting said transverse aperture, said aperture and said slot

2
being adapted to receive cross wires, and a nut adapted to be threaded upon said threaded-end for drawing the sides of said clamp toward one another and clamping 5 said wires together.

2. As an article of manufacture, a wire clamp for fences, comprising a slotted body portion, said body portion provided with a transversely extending aperture near the center thereof, said body portion provided with a threaded tapering end provided with a slot formed in said threaded end and intersecting said transverse aperture said apertured 10

threaded end constituting jaws, said aperture adapted to receive a vertical strand, said slot adapted to receive a longitudinal strand, and a nut screw-threaded upon said end and adapted to draw the jaws toward one another, and clamp said vertical strand in engagement with said longitudinal strand. 15 20

In testimony whereof I hereunto affix my signature in presence of two witnesses.

GEORGE H. FARNILO.
